UNITED STATES PATENT OFFICE.

PAUL H. SCHENDLER, OF ERIE, PENNSYLVANIA.

CLOTHES-WRINGER.

1,355,916.

Specification of Letters Patent. Patented Oct. 19, 1920.

Application filed January 5, 1920. Serial No. 349,496.

To all whom it may concern:

Be it known that I, PAUL H. SCHENDLER, a citizen of the United States, residing at Erie, in the county of Erie and State of Pennsylvania, have invented certain new and useful Improvements in Clothes-Wringers; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in clothes wringers and particularly to the construction of the frames and spring mechanism thereof and the combination of the parts of the wringer whereby its simplicity 20 of construction, strength and efficiency are improved.

The features of my invention are herein-
after fully set forth and described and illus-
trated in the accompanying drawings in
25 which:

Figure 1, is a side view in elevation of my improved clothes wringer.

Fig. 2, is a top or plan view of the same.

Fig. 3, is a vertical section of the same on
30 the line $\alpha-\alpha$ in Fig. 1.

Fig. 4, is an end view in elevation of one of the ends of the wringer frame.

Fig. 5, is a top or plan view of the same.

In these drawings A A are the ends of
35 the wringer frame; B a transverse rod se-
curing the lower ends thereof together, and
C the upper part of the frame securing the
ends of the frame together. In suitable
bearings D, D' mounted in the vertical slots
40 A' in the end frames A, A, wringer rolls
E, E' are mounted on suitable bearings e, e',
one of which, e', is extended to receive a
crank (not shown) for rotating the rolls
E E' in the usual manner.

45 The end frames A A I preferably make of
cast metal having a central, rectangular,
longitudinal slot A' extending from the top
thereof downwardly nearly to the lower end
A² of said end frames (see Figs. 4 and 5);
50 and said end frames are also provided with
flanges α (see Figs. 3 and 5); and with out-
turned ears a² a² (see Fig. 3), which ears
are provided with holes therethrough for
the bolts G.

55 I preferably provide tubular shells a' a'

which extend downwardly from the ears
a² a², which inclose the springs F hereafter
described; but it will be understood that the
shells a' a' are not essential to the successful
operation of the wringer.

60

Within the rectangular longitudinal slots
A' are placed journal bearing blocks D and
D', the block D' resting on the bottom of
the slots, and the block D being slideable in
said slots. Upon the blocks D' the journals
65 e' of the lower wringer roller E' rest, one
end thereof extending outwardly beyond the
end frame as far as may be desired to receive
a crank or other power-applying mechanism
(not shown).

70

Above the roller E' is the upper roller E,
the journals thereof extending transversely
through the slots A' in each end frame, upon
which the slideable blocks D rest. Upon the
upper ends of the end frames A A is placed
75 a plate C which extends from one end frame
to the other, and is provided with ears C'
which fit over the ears a² at the upper ends
of the end frames A A; said ears C' being
provided with holes which coincide with the
80 holes in the ears a² a² at the upper ends of
said end frames; and through said holes I
place the bolts G heretofore mentioned, and
upon which bolts G I place springs F, the
85 upper ends of which bear against the under
sides of the ears a² a² on said end frames,
and upon the lower ends of said bolts G are
placed nuts g by means of which the tension
90 of said springs can be regulated to draw the
plate C downwardly with such pressure as
may be desired. The plate C carries thumb
screws H H the lower ends of which engage
95 the bearing blocks D in the usual manner.

It will be seen from the foregoing that
when clothing passes between the rollers E
and E' the upper blocks D will be raised
upwardly in the slots A', which, through the
thumb screws H raises the plate C,
100 and through the bolts G compresses the
springs F.

The plate C is shown as provided with
releasing mechanism I, I' I'. This feature
however, though shown herein, has been
previously patented to me in my U. S. Pat-
ent No. 1,201,766, issued October 17, 1916,
105 and therefore forms no part of this inven-
tion.

The construction of end frames herein-
before described, enables me to use much
longer springs which give much greater re-
110

siliency than where such springs bear directly upon the bearing blocks of the upper roller, at the same time enabling me to use much shorter end frames than ordinarily, and with coiled springs.

Having thus fully described my invention so as to enable others to utilize the same, what I claim as new and desire to secure by Letters Patent is:

- 10 1. In a clothes wringer, bifurcated end frames, out-turned ears at the upper ends thereof, journal bearings between the two arms of said end frames, a top plate extending from one end frame to the other, thumb screws in the ends of said top plate and engaging the uppermost of said journal bearings, bolts passing through said top-plate and the ears on said end frames, springs on said bolts, and means on said bolts to press said springs upwardly against said ears, and said top-plate downwardly thereon, substantially as set forth.
- 15 2. An end frame for a clothes wringer having a central vertical slot therein open at its upper end and closed at its lower end, and longitudinal spring receiving recesses parallel with each side of said slot closed
- 20
- 25

at their upper ends and open at their lower ends, substantially as set forth.

3. In a clothes wringer the combination 30 of end frames having central longitudinal slots therein open at their upper ends and closed at their lower ends, flanges at each side of said slots, spring receiving recesses 35 in said end frames at each side of said central slot, said recesses being closed at their upper ends and open at their lower ends, a stationary roller bearing in the lower ends of said slots, a wringer roller journaled on said bearing, an upper roller, slidable bearings 40 in said longitudinal slots adapted to be pressed downwardly on the journals of said last mentioned roller, a top-plate, thumb screws therein engaging said slidable bearings, bolts passing downwardly through 45 said top-plate and said spring receiving recesses, springs around said bolts, and nuts on said bolts adapted to press said springs upwardly against the closed ends of said recesses and draw said top-plate downwardly 50 against the upper ends of said end frames, substantially as set forth.

In testimony whereof I affix my signature.
PAUL H. SCHENDLER.
